UNITED STATES PATENT OFFICE.

MAJOR DANE PORTER, OF BOSTON, MASSACHUSETTS.

THERMOSTAT.

SPECIFICATION forming part of Letters Patent No. 296,058, dated April 1, 1884.

Application filed December 11, 1883. (No model.)

To all whom it may concern:

Be it known that I, MAJOR DANE PORTER, a resident of Boston, in the county of Suffolk, of the Commonwealth of Massachusetts, but a 5 subject of the Queen of Great Britain, have invented a new and useful Improvement in Thermostats; and I do hereby declare the same to be described in the following specification and represented in the accompanying drawings, of which—

Figure 1 is a top view, Fig. 2 a front elevation, and Fig. 3 a rear view, of a thermostat embracing my invention, the nature of which is defined in the claim hereinafter presented.

15 The said thermostat is intended for use in a building, and to be so connected with the ground and main wires of an electric circuit as to be capable, when the springs or the abutments thereof of the thermostat are brought 20 into contact by expansion of either or both of such springs by heat to effect a closing of the circuit, to cause an alarm to be given at a distant station to which the circuit may be extended.

25 In the drawings, A denotes a plate, of hard rubber or other suitable electric insulating material, having at opposite parts of it two metallic circuit-wire clamps, B B, extending from one face of it. Between the said clamps 30 there are arranged, as shown, and suitably secured to the plate at or near one end of each, by screws *a a'*, two separate volute or bow

springs, C C', made of the usual thermostatic metal, which near their toes or free ends are turned or bent toward each other, so as to form 35 to each an abutment, *b b*. These abutments need not necessarily be of the form represented, as they may be otherwise shaped or adapted, in order to abut together by movements of the springs induced by heat or a rise in temperature. 40 From the heel or fastening-head *c* of one of the said springs, a small tooth is extended into a groove, *e*, formed in and around the shank of a screw, D, that is screwed into and through a projection, *f*, extending from the 45 plate A. This screw and tooth are for adjusting the abutment of the spring C' in distance from the spring C or its abutment, the said spring C' being free to turn on its screw *a'*. From the fastening-screws, or from the heels of 50 the springs, metallic wires E are extended to the two clamps B B.

I claim—

In a thermostat, the two springs C C', having their abutments *b b* near each other, and 55 one spring provided with a tooth, in combination with an adjusting-screw, D, having a groove, *e*, which groove engages the tooth on the spring, as set forth.

MAJOR DANE PORTER.
